UNITED STATES PATENT OFFICE.

ALFRED C. STEWART, OF LOS ANGELES, CALIFORNIA.

ROTARY DRILLING APPARATUS.

1,068,015.

Specification of Letters Patent.

Patented July 22, 1913

Application filed December 12, 1911. Serial No. 665,390.

To all whom it may concern:

Be it known that I, ALFRED C. STEWART, a citizen of the United States, residing at Los Angeles, in the county of Los Angeles and State of California, have invented a new and useful Rotary Drilling Apparatus, of which the following is a specification.

This invention relates to an apparatus for drilling rotary wells, and one of the main 10 objects of the invention is to obviate the use of the drill tube and employ a small shaft extending down through the casing and to rotate the shaft at a high speed in order to transmit the required power and 15 employ suitable gearing between the shaft and the drilling bit to reduce the speed so that the drilling bit will be driven at the desired velocity. By dispensing with the drill tube the great expense thereof is eliminated, 20 the cost of the small shaft being very much less. In addition to this a great saving in time is effected because when the drill tube is used much time is required in screwing and unscrewing the sections of drill tube 25 when removing the drill or replacing the drill, while with the small shaft the sections thereof may be quickly coupled or uncoupled.

A further object is to lock the gearing for 30 operating the drilling mechanism to the outer casing so that when operating the bit will be maintained in the same relative position with respect to the casing, a further object being to provide means for unlocking 35 the drill operating mechanism when it is desired to raise the drilling mechanism out of the casing. Both the locking and unlocking operation may be performed from the top of the well.

40 A further object is to provide an expandable bit with means for expanding or contracting the bit when at the bottom of the casing, and to accomplish this through the medium of the small operating shaft above 45 referred to.

50 Referring to the drawings:—Figure 1 is a vertical longitudinal section through the lower portion of the casing and through the drilling mechanism, showing the parts in position for operation. Fig. 2 is a view similar to Fig. 1, but showing only the upper portion thereof, and illustrates a different position of the device for locking the drilling mechanism to the casing. Fig. 3 is a view similar to Fig. 1 showing the bit contracted. Fig. 4 is an enlarged section on

line x^4-x^4 Fig. 1. Fig. 5 is an enlarged section on line x^6-x^5 Fig. 1. Fig. 6 is an enlarged section on line x^6-x^6 Fig. 1. Fig. 7 is a section on line x^7-x^7 Fig. 6. Fig. 8 is a section on line x^8-x^8 Fig. 7.

1 designates the outer casing which is constructed in the usual manner but provided with a series of holes 2 formed at the coupling 3.

65 The drill operating mechanism consists of a barrel 4 in the lower end of which is a sleeve 5 which is internally threaded and is screwed to a hollow arbor 6 which is rotatably mounted in bearings 7 and 8 which are supported by webs 9 from the barrel 4. The upper end of the arbor 6 has a flange 10 on which are journaled a pair of idle pinions 11 which mesh with a driving pinion 12 splined on a driving shaft 13. The shaft 13 70 has a relatively small diameter, as shown, and passes through the hollow arbor 6, being rotatable and also slidable therein. The pinions 11 also mesh with an internal gear 14 which is secured to the barrel 4.

80 Formed as part of the sleeve 5 is a bit comprising a conical portion 15 which has several inserted cutters 16, and a series of radially adjustable cutters 17. A fluted point 18 is screwed to the conical portion 85

15. Each of the cutters 17 has a pin 19 which engages in a slotted scroll 20 which is rotatable above the conical portion 15 and has a bearing in the sleeve 5. The scroll 20 has two pins 21 on each of which is journaled a pinion 22. The pinions 22 mesh with a stationary internal gear 23 which is formed in the sleeve 5 and also mesh with a pinion 24 which is arranged concentrically 90 with the shaft 13 and is mounted on a sleeve 25 with sufficient friction to be operated thereby. The sleeve 25 has a squared central hole 27 which is adapted to receive the squared lower end 28 of shaft 13. A sleeve 29 is arranged on the lower end of the casing 95 1 and has an inwardly directed flange 30 which projects inwardly beyond the casing 1, acting as a support for the lower end of the barrel 4. A series of slots 31 are cut in the flange 30 to permit the passage of 100 water which is caused to be circulated down into the casing past the barrel and out of the bottom.

105 Near the upper end of the barrel 4 are four radial studs 32, in each of which is 110 slidably mounted a locking pin 33 with a round head 34. Each pin 33 projects

through the wall of the barrel 4 and is adapted to be engaged with a hole 2. A coil spring 35 presses each pin 33 inwardly against a tapering sleeve 36, the upper end 5 of the sleeve 36 being slidably supported in a neck 37 on the end of the barrel 4 and its lower end being slidably in a bearing 38 supported by webs 39 from the barrel. A coil spring 40 presses against the upper end 10 of the sleeve 36 and tends to depress the same. The shaft 13 extends through the sleeve 36 and through a stuffing box 41 on neck 37. A collar 42 is rigidly secured to the shaft 13, and when the shaft 13 is pulled 15 up the collar 42 will lift the sleeve 36 and permit the pins 33 to move inwardly.

43 is a hollow shaft which is coupled to the shaft 13 and which extends to the top of the well.

20 In operation the parts stand as shown in Fig. 1, the cutters 17 being expanded and the shaft 13 is driven at a comparatively high speed, say, for example, 800 R. P. M. The pins 33 engage the recesses 2 and lock 25 the barrel against longitudinal movement and against rotation. It is to be noted that when the parts are in operating position the squared end of shaft 13 does not engage the sleeve 25, this engagement only 30 taking place when the drilling bit is to be expanded or contracted. As the shaft 13 rotates the pinion 12 drives the idle pinions 11 and the latter, which mesh with stationary gear 14, are caused to travel bodily 35 around the stationary gear 14, and as the pinions 11 are thus caused to travel bodily they carry with them the sleeve 6, and as the sleeve 6 rotates it carries with it the flange 5 and bit 15 which are attached to it. 40 As the bit thus rotates the scroll 20 and gearing combining therewith rotate bodily with the bit but have no operating function at this time. As the drilling proceeds the casing is lowered in well-known manner, a 45 water circulation being maintained down casing and out through the spaces 31.

When it is desired to raise the bit the shaft 13 is stopped from rotation and is moved farther down so that its squared end 50 is engaged in the sleeve 25. Rotation of the shaft 13 then drives pinion 24 and the latter acting through pinions 22 which are in mesh with internal gear 23 causes the scroll 20 to be revolved, the pinions 22 having a 55 planetary movement, and as the scroll 20 is thus rotated it acts upon the pins 19 to move the cutters 17 radially inward. It should be observed that rotation of the scroll is effected even though the flange 5 60 is also rotating, because it is only necessary that there be a relative movement between shaft 13 and flange 5 which has gearing 23, and as shaft 13 revolves at comparatively high speed there is always relative movement, even when flange 5 is rotating. When

the scroll has moved the cutters 17 to their inward positions no breakage can occur if the shaft 13 is not stopped from rotating at that time because the sleeve 25 will permit the pinion 24 to turn. After the bit has been contracted the shaft 13 is then raised 70 until the collar 42 strikes sleeve 36, and continued upward movement of shaft 13 lifts sleeve 36 permitting pins 33 to be moved inwardly by springs 35 and disengage locking 75 recesses 2, the parts then being in the position shown in Fig. 2, the bit and all parts for driving the same may then be lifted up bodily through the casing, the collar 42 supporting the sleeve 36 and the sleeve 36 compressing the coils of spring 40 into contact 80 and thereby positively supporting the barrel 4. When the bit is to be lowered into the well the parts have this same position and they are lowered until the lower edge 85 of the barrel 4 strikes the flange 30 which arrests further downward movement of the barrel and the shaft 13 is moved still farther downward sufficiently to cause the collar 42 to move away from the sleeve 36 and permit the latter to be moved down by spring 40 sufficiently to push pins 33 outward into engagement with locking recesses 2. The shaft 13 is then moved still farther 90 down to engage the pinion 24 and then rotated to operate the scroll 20 and slide out the cutters 17 after which the shaft 13 is moved up into the position shown in Fig. 1 to disengage the pinion 24. The parts are then in position for drilling. 95

What I claim is:

1. In a rotary drilling apparatus, a bit, cutters on the bit, the well casing, a shaft extending down from the top of the well casing, and gearing between said shaft and 105 bit for driving the bit at a lower speed than the shaft.

2. In a rotary drilling apparatus, a bit, cutters on the bit, the well casing, a shaft extending down the well casing, gearing between said shaft and bit for driving the bit at a lower speed than the shaft, and gearing adapted to be engaged by said shaft for expanding or contracting said cutters. 110

3. In a rotary drilling apparatus, a barrel 115 adapted to be lowered down the well casing, a bit revolubly mounted at the lower end of said barrel, a small shaft extending down the well casing into said barrel, and gearing within said barrel between the shaft and bit 120 for driving the bit at a slower speed than the shaft.

4. In a rotary drilling apparatus, the well casing, a barrel adapted to be lowered down the well casing, a bit revolubly mounted at 125 the lower end of said barrel, a small shaft extending down the well casing and into said barrel, gearing within said barrel for driving said bit at a slower speed than said shaft, and means operated by a longitudinal 130

movement of said shaft for locking or unlocking said barrel from said well casing.

5. In a rotary drilling apparatus, the well casing, a barrel adapted to be lowered down the well casing, a bit revolvably mounted at the lower end of said barrel, a small shaft extending down the well casing and into said barrel, gearing within said barrel for driving said bit at a slower speed than said shaft, means operated by a longitudinal movement of said shaft for locking or unlocking said barrel from said well casing, adjustable cutters on said bit, and gearing adapted to be engaged by longitudinal 15 movement of said shaft for adjusting said cutters.

6. In a rotary drilling apparatus, the well casing, a barrel adapted to be lowered to the bottom of the well casing, a bit revolvably mounted at the bottom of said barrel, adjustable cutters on said bit, a small shaft extending down the well casing and into said barrel, gearing for adjusting said cutters, means for frictionally driving said gearing and having a detachable engagement with said shaft.

7. In combination, the well casing, a bit therein, adjustable cutters on the bit, a scroll revolvably mounted with respect to the bit, lugs on the cutters engaging said scroll, a shaft extending down the well casing and longitudinally movable, and means adapted to be engaged by longitudinal movement of the shaft for operatively connecting the shaft with said scroll.

8. In combination the well casing, a bit

therein, adjustable cutters on the bit, a scroll revolvably mounted with respect to the bit, lugs on the cutters engaging said scroll, gearing for driving said scroll, a shaft extending down the well casing, and means for detachably engaging said shaft with said gearing.

9. In combination, the well casing, a bit therein, adjustable cutters on the bit, a scroll revolvably mounted with respect to the bit, lugs on the cutters engaging said scroll, pinions pivoted on said scroll, a stationary internal gear meshing with said pinions, a driving pinion meshing with said first pinions, and a shaft extending down the well casing, and means for engaging said shaft with said driving pinion.

10. In combination the well casing, a bit therein, adjustable cutters on the bit, a scroll revolvably mounted with respect to the bit, lugs on the cutters engaging said scroll, pinions pivoted on said scroll, a stationary internal gear meshing with said pinions, a driving pinion meshing with said first pinions, a shaft extending down the well casing, frictional means for rotating said driving pinion and having a detachable engagement with said shaft.

In testimony whereof, I have hereunto set my hand at Los Angeles, California this 28th day of November, 1911.

ALFRED C. STEWART.
